UNITED STATES PATENT OFFICE.

DWIGHT S. RICHARDSON, OF BROOKLYN, NEW YORK.

RADIATOR OR HEATING-DRUM.

SPECIFICATION forming part of Letters Patent No. 361,321, dated April 19, 1887.

Application filed October 1, 1883. Serial No. 107,823. (No model.)

To all whom it may concern:

Be it known that I, DWIGHT S. RICHARDSON, a citizen of the United States, and a resident of Brooklyn, in the county of Kings and State 5 of New York, have invented certain new and useful Improvements in Heating-Drums or Radiators, of which the following is a full, clear, and exact description.

The invention relates particularly to drums 10 which are employed in connection with the combustion-chambers of hot-air furnaces; but my improvements may be applied to heating-drums which are to be used in other connections.

15 In United States Patent No. 272,326, issued to me February 13, 1883, is shown a drum the walls of which are cast in one continuous piece of metal, the space inclosed therein being divided horizontally by a diaphragm, two flues 20 being thus formed for the passage of the products of combustion, the object of the construction being to impart to the ascending currents a zigzag course, first toward the front and then toward the rear of the drum, so as to 25 insure thorough utilization of the heat which is contained in such products. In United States Patent No. 279,666, issued to me June 19, 1883, the same general characteristics are embodied; but the top and sides only of the drum 30 are of one continuous casting, the bottom being a separate and distinct plate or sheet attached to the walls at their base in any suitable manner, and provision is made for either casting the diaphragm with the walls or for 35 its separate formation and subsequent attachment thereto. These constructions combine various advantages, and in their perfect utilization of the heat contained in the products of combustion and in their prevention of the 40 escape of deleterious gases from the drum into the surrounding hot-air chamber they give satisfactory results. It has been found, however, that under certain circumstances different portions of the walls of the drum expand and contract 45 unequally, sometimes causing fracture of some one of the parts, to the consequent detriment of the purity of the contents of the air-chamber, and to avoid this I have devised this invention, which consists in constructing 50 a drum which, while of the same general form as those hereinbefore described, is constituted of two horizontal sections, one of which rests

loosely upon the other, the diaphragm being placed in the same relation to the upper and lower portions of the drum as before—that is, 55 at about its mid-height.

In the drawings, Figure 1 represents in vertical section a drum of the described character, in which is shown a groove or packing-receptacle formed with the lower section of the 60 drum, the diaphragm resting loosely upon the top of the inner wall of the cup, which constitutes, also, the upper extremity of such lower section. Fig. 2 shows a similar construction, the diaphragm having depending or flanged 65 edges, which rest in the receptacle inside the lower extremity of the upper section. Fig. 3 is a vertical longitudinal central section showing the adaptation of the radiator for use in connection with one form of heating-furnace, 70 the diaphragm being arranged as represented in Fig. 2.

It will be seen that under this construction all the parts are loosely fitted together, and are free to expand and to contract without 75 danger of fracture or strain.

In Figs. 4, 5, and 6, each a vertical section, are represented modifications of the above-described construction, Fig. 4 showing the receptacle formed as in Fig. 1, and having a diaphragm cast integral with the upper section 80 of the drum; Fig. 5 showing the receptacle as in Fig. 1, but with the diaphragm forming an inseparable portion of the lower section, and Fig. 6 showing a two-plate or double dia- 85 phragm, one plate being cast with the walls and extending across the lower extremity of the upper section, and the other plate being cast with the walls and extending across the upper extremity of the lower section of the 90 drum. I do not herein claim these modified forms of construction, but I reserve the right to make a separate application for a patent therefor.

In all the figures A is the upper section, and 95 B is the lower section, of the drum; C is the packing-receptacle, and D is the diaphragm; and in Fig. 5, d d are the downwardly-extended edges of the diaphragm, forming flanges which, in common with the edge of the upper section, 100 rest within the packing-receptacle.

It will be understood, although it is not material to the points of novelty herein presented, that an orifice is provided in the diaphragm

in each of these representations, so that the circulation of the products through the drum is first from any suitable fire-chamber or other source of heat below the drum into the lower flue of the same, and from the lower flue through an orifice in the diaphragm into the upper flue, through which they pass to the exit-opening, the same as in the patents hereinabove referred to.

10. A heating-drum composed of two distinct sections, the upper resting in a "sand-joint" upon the lower, has before been made.

My construction combines the advantages of the loose joint with those of the diaphragm, 15 which converts the drum-chamber into two horizontal flues.

All or either of the parts may be of either cast, wrought, or sheet metal, the former, however, being ordinarily employed.

20. Having thus described my invention, what I desire to claim, and secure by Letters Patent, is—

1. A radiator or heating-drum which con-

sists of two distinct sections, one of which rests loosely upon the other, and a diaphragm which 25 is placed at or near the point of junction of the two sections and which divides the same into two parallel horizontal flues.

2. In a radiator or heating-drum, the combination of an upper section, a lower section, 30 and an independent diaphragm which is loosely placed at or near the point of junction of the two sections and which divides the same into two flues.

3. In a radiator or heating-drum, the combination of a lower section which is provided with a packing-receptacle, an upper section which is adapted to rest in the packing-receptacle, and an independent diaphragm which 35 is also adapted to rest in the packing-receptacle. 40

DWIGHT S. RICHARDSON.
